UNITED STATES PATENT OFFICE.

ELLY ZACHARIE, OF NEW YORK, N. Y., ASSIGNOR TO BAZIN & SARGENT,
OF SAME PLACE.

DESIGN FOR CAKE SOAP.

SPECIFICATION forming part of Design No. 16,535, dated February 16, 1886.

Application filed September 16, 1885. Serial No. 177,309. Term of patent 14 years.

To all whom it may concern:

Be it known that I, ELLY ZACHARIE, a citizen of the United States, residing at New York, in the county of New York and State of New York, have invented and produced a new and original Design for Cake Soap, of which the following is a specification, reference being had to the accompanying drawings, forming part thereof.

10 My invention consists in a design for cake soap; and it consists in the cake of soap having the conventionalized shape of a closed oyster-shell.

15 In the accompanying drawings, Figure 1 is a view of one of the cakes of soap, and Fig. 2 represents a group of said cakes arranged in position in a saucer resting on sea-weed.

20 The leading feature of my design consists in the conventionalized representation of a closed oyster-shell.

A represents a cake of soap having the conventionalized shape and appearance of an oyster with the shell closed, as the latter looks when taken from the water cleanly washed.

B represents a saucer, and C the sea-weed in which the cakes of soap are packed.

Having fully described my invention, what I claim as new, and desire to secure by Letters Patent, is—

The design for a cake of soap, consisting of 30 the conventionalized representation of a closed oyster-shell, substantially as shown and described.

ELLY ZACHARIE.
